UNITED STATES PATENT OFFICE.

JAY E. DUNN, OF BROOKLYN, NEW YORK, ASSIGNOR TO NOVO MANUFACTURING COMPANY, OF NEW YORK, N. Y., A CORPORATION OF NEW YORK.

ELECTRIC BATTERY.

1,318,364.

Specification of Letters Patent. Patented Oct. 14, 1913.

Application filed September 23, 1916. Serial No. 121,742.

To all whom it may concern:

Be it known that I, JAY E. DUNN, a citizen of the United States, residing at Brooklyn, in the county of Kings and State of New York, have invented certain new and useful Improvements in Electric Batteries, of which the following is a specification.

My invention relates to an improvement in electric batteries; particularly batteries of the type employed to supply current for incandescent lamps in torches and flashlights.

The primary object of my invention is to provide a vessel or container for the chemical substances by whose action upon the electrodes of the battery electric energy is produced; the container being of such construction as will not only enable it to be easily, quickly and cheaply manufactured, but also permit the merits of the battery when finished to be enhanced, and the durability and efficiency thereof to be measurably increased.

The above and other objects of my invention will appear from the following description, taken in connection with the accompanying drawings; whereon several embodiments of my invention are illustrated. This disclosure, however, is to be construed as explanatory only; and embodiments of my invention other than those actually shown herein may of course be used; to the full extent indicated by the general meanings of the terms in which the claims appended hereto are expressed.

On said drawings:

Fig. 1 is a view of a blank out of which the body or main portion of my improved container is made;

Fig. 2 is a side view when the blank has been worked to cause it to assume the required shape;

Fig. 3 is a side elevation, partly in section, of my container, showing both the main portion and the bottom;

Fig. 4 is an end view of the main portion of the container;

Fig. 5 is a view, similar to Fig. 2, of a modified form of body for a container;

Fig. 6 is a view, similar to Fig. 3, of the body referred to in connection with Fig. 5, with the bottom of the container added.

Fig. 7 is an end elevation of the modified container body;

Fig. 8 is a plan view of the bottom of the container;

Fig. 9 is a side elevation thereof;

Fig. 10 is a modified form of blank for making the body or main portion of a container;

Fig. 11 is a side elevation, partly in section of this modified blank, after shaping 60 the same;

Fig. 12 is a similar view of the same, with the bottom added;

Fig. 13 is an end view of the construction shown in side elevation on Fig. 11; and 65

Fig. 14 is a longitudinal sectional view of a battery including my container.

The same numerals of reference identify the same parts throughout.

I wish to state at the outset that heretofore 70 containers for electric batteries for flashlights and the like have been generally made by soldering a tubular body of conducting material to a bottom of similar material; whereby such containers have been composed 75 entirely of metal. Such a method is comparatively expensive; requiring relatively large quantities of metal, and entailing a number of difficult operations to get the parts permanently assembled; and it has the 80 further disadvantage that the bottom is not always united to the body in such a way as to make the container perfectly leakproof. In the practice of my invention, such objections are largely obviated; and at the same 85 time I secure certain important advantages which are clearly set forth subsequently in this specification.

In the detailed account of my invention below, reference is first had to Figs. 1 to 9. 90 inclusive. On these views, I employ the numeral 1 to indicate a sheet of electrically conductive material; such as zinc or other suitable metal; shown in the form of a blank in Fig. 1; said sheet being adapted to be 95 rolled or otherwise worked into the tubular form illustrated in Figs. 2, 3, 4, 5, 6 and 7. After being worked in such fashion, it will preferably be cylindrical, with its opposite edges 2 overlapping; whereby it may serve 100 as the main portion of a container in which the chemicals of an electric battery are received. In the embodiment of my invention portrayed in Figs. 2, 3 and 4, the metal blank 1 is made cylindrical only; but in the 105 modification depicted in Figs. 5, 6 and 7, the blank is subjected to a further operation to cause one terminal edge to extend inward, making a rim or flange 3. In both these forms of my improvement, an imper-

forate wad 4 of insulating material; for example, paper, cardboard or other substance, fibrous or non-fibrous, is employed to close one end of the main portion 1, and 5 constitute the bottom of the container.

The wad 4 in any case will be located adjacent one end of the main portion 1, and preferably as near to the terminal edge of the same as it can be placed. In the form 10 of my invention illustrated in Figs. 2, 3 and 4, this wad will be flush with the terminal edge; while in the modification shown in Figs. 5, 6 and 7, the wad will not be quite flush with the terminal edge, but will engage 15 the rim 3 and abut against the inner face thereof. I make the wad 4 of such size that its periphery will be encircled snugly by the main portion of the container when the wad is properly disposed therein; thus giving 20 a fairly tight fit; and this wad is also treated so as to coat it; and, if possible, impregnate it, as can easily be done when the wad is of a fibrous nature, with an insulating substance indicated at 5 in Figs. 8 and 25 9; for a purpose which will be explained fully hereinafter.

The overlapping edges 2 of the portion 1 are secured by soldering or in any other practicable way. If desired, these edges 30 may be fastened by clenching, and soldering dispensed with, as will be understood. When the bottom is to be applied, the wad 4 is inserted at one end of the portion 1 and pushed through to the other with a ram- 35 mer; and when this operation is being performed, the portion 1 should first be set upright on a flat surface, so that the wad can easily and quickly be forced to assume its correct position.

40 Figs. 10, 11, 12 and 13 present another form of my improved container. This form is made exactly like that shown in Figs. 5, 6 and 7, with the difference that the metal blank 1 is stamped out so that it has teeth 45 or points 6 at one end. After the blank is made as in Fig. 10, it is shaped like a cylinder and its overlapping edges 2 secured together; and the teeth 6 are bent over, as shown in Figs. 11, 12 and 13 in the same 50 manner as the rim 3. Usually the wad 4, which is illustrated in position in the portion 1 on Fig. 13, is inserted into the main portion in this modification of my container, and the teeth 6 bent over, at a single operation; 55 and when this container is completed, the wad will be adjacent the end of the main portion, as in the preceding forms.

When any of the forms of container embodying my invention is finished; as by 60 shaping the main portion 1 and adding the wad 4, it may be charged in the usual way. As seen in Fig. 14, the portion 1 constitutes one of the electrodes of the battery; and a member including a rod of carbon 7 with a 65 cap 8, constitutes the other. This member

will be centrally located in the container, with its inner end in relatively close proximity to the bottom; and its opposite end, bearing the cap 8, projecting out of the container for a slight distance. Around this 70 member is a core 9, consisting of a mixture of manganese dioxide and graphite, moistened with a solution of ammonium chlorid or other suitable ingredients; this core being provided with a covering of cloth 10, secured by a cord 11. Between the core 9 and the inside surface of the portion 1 is an insulating ring, such as a rubber band 12, designed to hold the core 9 out of contact with the portion 1 and thus prevent a short circuit in the battery. The space wherein the band 12 is placed is filled with a "paste" 13, containing ammonium chlorid and other compounds, to react upon the ingredients of the core 9 and give the chemical reactions 80 that will generate an electromotive force between the electrodes 1 and 7. Above the core 9 and paste 13 will be a layer of wax 14; and over the wax 14 is a perforated closure of paper or other insulation 15. A disk 90 16, of paper or the like, is also put into the container on the wad 4, before the core 9 and paste 13 are introduced into the portion 1.

In manufacturing the battery, the core 95 9 with the member 7 inside it and the band 12 surrounding it, is inserted into the container first; and the "paste" 13 is next supplied. The container is then subjected to the action of heat, as by putting it into a 100 bath of hot water; whereby the "paste" 13 is coagulated and thickened. I then pour in the paraffin 14, slip the closure 15 over the member 7, and affix the cap 8 thereto.

The insulating substance or plastic 5 on 105 the wad 4 preferably includes paraffin and rosin. During the hot water bath, the paraffin is softened and becomes partly fluid; whereby it is enabled to fill every minute crack or opening between the inner face of 110 the portion 1 and the periphery of the wad. As a result, the paraffin acts as a seal; making a perfect leakproof joint between the portion 1 and the wad 4; and the rosin, which 115 also becomes plastic, has the effect of making the contacting faces of the portion 1 and the wad 4 engage and stick tightly together. Hence the wad not only closes up the one end of the portion 1 in such a way as to obviate the risk of loss of the contents by leakage, by reason of the presence of the paraffin; but it also, by the action of the rosin, 120 is enabled to resist being pushed either into or out of the portion 1, in the form shown in Figs. 2, 3 and 4, and into the portion 1 125 in the forms of my invention illustrated in Figs. 5, 6, 7, 11, 12, and 13; the rim 3 and teeth 6 holding the wad against displacement outward of the portion 1.

From the foregoing, the practical utility 130

and advantages of my invention will be apparent. By using the insulating wad 4, I am enabled to save metal and to assemble the parts of the container in a quicker, easier and cheaper manner; since the preparation of the wad with the insulating substance 5 thereon and its insertion into the main portion of the container involve less labor and expense than the making of a metal disk 10 and the soldering of the latter to the main portion 1.

Furthermore, the purpose of the substance 5, including the paraffin and rosin, or equivalent substances which I may of course employ, always gives a tight, leak-proof connection between the portion 1 and the wad 4; because of the effect of the hot water bath in which the battery is dipped; and this tight, leakproof connection is not dependent upon the carefulness of the operative, as is the case when a metal disk is soldered to the portion 1 by hand. Hence the desired result is infallibly obtained, no matter how ignorant or careless a workman may be; and a defective container cannot be produced. When metal bottoms, soldered to the portion 1, are used instead of the wads 4, the number of containers that are defective and leaky is from five 30 to ten per cent., depending on the individual workman.

The importance of obviating leakage is due to the fact that leakage would not only mean loss of the contents of the battery; but also would be capable of giving rise to local action and possible short-circuiting between adjacent cells or batteries when a number thereof is used. These batteries are placed side by side in a casing, with insulating sheets between them. If leakage through the bottom of the container occurred, the insulation would be in danger of disintegrating and allowing the escaping contents to creep from one container to a neighboring one; with consequent impairment of the action of the battery and reduction of output.

All such drawbacks are entirely overcome by means of my invention; and in addition I produce a battery of superior merit, capable of higher efficiency, greater durability, and longer life under all conditions of service.

The particular chemical substances used to make up the core 9 and the "paste" 13 surrounding it are of course no part of my invention; as they may be any of the well known compounds or mixtures employed in batteries of this character. I further allow myself the same freedom of choice

with regard to the materials used in the making of the portion 1, the wad 4, the substance 5, and the member 7.

My improved battery container may of course be made in any size, and the number 65 of teeth 6 may be varied at will. Likewise, my container may be utilized for batteries used for other purposes than in flashlights.

Having described my invention, what I believe to be new and desire to secure and protect by Letters Patent of the United States is:—

1. A container for an electric battery comprising a main portion of electrically conductive material and an imperforate wad 75 of insulating material in said portion adjacent one end thereof, said wad constituting the bottom of the container, said portion extending inward adjacent said end to retain said wad against displacement 80 therethrough.

2. A container for an electric battery comprising a tubular main portion of electrically conducting material, an imperforate wad of insulating material in said portion, 85 having its periphery engaged thereby, said wad being located adjacent one end of the main portion and constituting the bottom of the container, and an insulating substance coating the wad and engaging the 90 wad and the main portion, said substance including an ingredient to make a leakproof joint between the wad and the main portion, and an adhesive to secure the wad and the main portion together. 95

3. A container for an electric battery comprising a tubular main portion of electrically conducting material, said portion having one terminal edge provided with inward extending teeth, and an imperforate wad of 100 insulating material in said portion abutting said teeth and constituting the bottom of the container.

4. A container for an electric battery comprising a tubular main portion of electrically conductive material, and an imperforate wad of insulating material in said portion, adjacent one end, and constituting the bottom of said container, said tubular main portion extending inward adjacent said end 110 to engage the wad and to prevent displacement of the wad through said end, and means engaging the wad in the main portion to make a leak-proof joint between the wad and the main portion and to secure the 115 wad and the main portion together.

In testimony whereof, I have signed my name to this specification this 18th day of September, 1916.

JAY E. DUNN.
